UNITED STATES PATENT OFFICE.

WILLIAM H. KELL, OF CHICAGO, ILLINOIS, ASSIGNOR TO SHEA SMITH & COMPANY, OF CHICAGO, ILLINOIS.

ADJUSTABLE POST FOR BINDER-FILES.

SPECIFICATION forming part of Letters Patent No. 731,914, dated June 23, 1903.

Application filed January 19, 1903. Serial No. 139,702. (No model.)

To all whom it may concern:

Be it known that I, WILLIAM H. KELL, a citizen of the United States, residing at Chicago, in the county of Cook and State of Illinois, have invented certain new and useful Improvements in Adjustable Posts for Binder-Files, of which the following is a specification.

This invention relates to posts for use in connection with binder-files employing adjustable locking binder-bars; and the present invention is intended to provide a post which will enable the binder-bar to be raised and the files slipped into place without extending the entire post to allow for the raising of the binder-bar, the entire device in use being simple and compact, occupying but a slight amount of space, and being adapted for use with file-binders of varying capacity.

20 The invention consists in the features of construction and combinations of parts hereinafter described and claimed.

In the drawings, Figure 1 is a side elevation of an ordinary file-binder employing a binder-bar; Fig. 2, a similar view showing the cover raised; Fig. 3, a rear end elevation of the file-binder of Figs. 1 and 2; Fig. 4, a portion of a file, showing the nature of the hole and slot therein; Fig. 5, a side elevation of the post closed; Fig. 6, a similar view showing the post open; Fig. 7, a view showing the outer sleeve or casing cut away; Figs. 8, 9, and 10, details of the parts composing the extensible post; Fig. 11, a slight modification of the same, and Figs. 12 and 13 views showing the post in combination with extensible sections.

The post is used in connection with an ordinary file-binder having a bottom cover A and a hinged top cover A', exterior of which is an adjustable clamping binder-bar B, of any well-known construction, operated by means of an adjusting-screw b or otherwise.

The extensible post, which more particularly forms the subject-matter of this invention, is preferably mounted within a socket C, which is screwed into the lower cover of the file-binder by means of a screw-threaded

stud c', and said socket is provided with a recess c, into which is screw-threaded the 50 stud d of the fixed section D of the extensible post. The fixed section is provided with a slotted tongue d', having side walls d² and a cross-head d³, as shown in Fig. 8, which tongue is of the same width as but of less diameter 55 than the body of the fixed member. A movable member E of the same diameter as the fixed member consists of a body portion e and a slotted portion e', which slotted portion fits over the slotted tongue on the fixed member 60 and is held thereon and prevented from being withdrawn therefrom by means of a cross-pin e². (Best shown in Fig. 9.) The extensible member is provided on its head with a screw-threaded recess e³, into which is screwed 65 the stud f of the head F, as shown in Fig. 9. Around the fixed and movable members is a sleeve or casing G of a shape, as shown, to conform to the curvature of the members, although it is obvious that the latter might be 70 made square or angular rather than round. In order to prevent the fixed member from being withdrawn from the casing or sleeve, a pin g is passed through the fixed member and the sleeve or casing, holding the two into firm and 75 rigid contact with one another and preventing the withdrawal of the fixed member.

In Fig. 11 a slight modification of the arrangement hitherto described is shown in which the slotted tongue of the fixed member 80 is dispensed with and a cross-pin J inserted to take the place of the cross-head d³ of the tongue. The extensible member in this case is the same as that hitherto described, and the only difference in construction is that the 85 side walls d² of the slotted tongue are dispensed with, making the structure less rigid and substantial than that hitherto described.

In Fig. 12 is shown a post provided with an intermediate section H, which latter is inserted between the extensible post and the socket and is provided with a stud h and a recess h', the former of which screws into the socket and the latter of which receives the stud on the fixed member of the extensible 95 post.

In Fig. 13 is shown a section adapted for use with the post in its extended relation. The section consists of a cylindrical tube I of the same diameter as the sleeve or casing, 5 within which, at the outer end thereof, is a plug i, from the inner face of which projects a stud i', and in the outer face of which is a recess i², into which may be screw-threaded another section of a head if so desired. The 10 plug is held in place within the tube by means of a pin i³ passing therethrough. The section last described enables the extensible post to be extended and virtually formed into a slotted post by the simple operation of screwing the section thereonto, thereby greatly enhancing the value of the extensible section 15 and increasing its adaptability to varying conditions.

The files are provided near their edge with 20 holes K of a diameter to encircle the posts, and a slot k is cut to the edge of the file, thereby enabling the same to be slipped onto the side of the post instead of over the top.

In use the files are slipped onto the post and 25 the upper cover, carrying the binder-bar, brought down tightly thereonto. The binder-bar is then locked onto the post, which tightly clamps the same, and said clamping operation may be made to slightly compress the 30 sleeve or casing, thereby contacting the clamping and movable section within and preventing the withdrawal or displacement of the movable section as long as the binder-bar remains locked. When it becomes necessary 35 to insert new files into the binder, the binder-bar is unlocked, releasing the movable section within the casing and allowing the movable section to be withdrawn, as shown in Figs. 2 and 3, whereby the binder-bar and 40 upper cover may be raised from the sleeve or casing up into position upon the movable section, releasing the pressure on the files and allowing additional files to be inserted into place. When the latter have been inserted 45 into place, the upper cover is again brought down thereonto, causing the binder-bar to once more encircle the sleeve or casing. The movable section is then pressed down into the sleeve or casing and the binder-bar is locked 50 thereonto, compressing the sleeve or casing and clamping the movable section in place. The operation in respect to the post of Fig. 11 is precisely the same as that hitherto described. If the size of the file is so much increased 55 that it becomes necessary to lengthen the rod, such a result may be accomplished either by means of an intermediate section, as shown in Fig. 12, or by means of an exterior section, as shown in Fig. 13. In the latter case it will not be necessary to remove the 60 files from the extensible post, but the exterior section may be immediately inserted thereonto, transforming the extensible post into a substantially solid post, onto which 65 may be fitted another extensible post, if so

desired. In this way the length of the post may be indefinitely increased without removing any of the files from the binder or disturbing them in any way.

What I regard as new, and desire to secure 70 by Letters Patent, is—

1. A post for binder-files which employ binder-bars, which consists of a fixed section, a slotted movable section provided with a stop or abutment closing the slot, a sleeve or casing fixedly attached to the fixed section, and an abutment extending across the shell or casing through the slot in the movable section and adapted to contact with the stop or abutment in the movable section and prevent 75 the withdrawal thereof, substantially as described.

2. A post for binder-files which employ binder-bars, which consists of a fixed section terminating in a screw-threaded stud and provided with a slotted tongue, a slotted movable section adapted to inclose the tongue and provided with a pin or stop passing through the slot in the tongue to prevent the withdrawal of the movable section therefrom, a 85 sleeve or casing fixedly attached to the fixed section inclosing the fixed and movable sections when in retracted relation, and a head on the movable section, substantially as described.

3. A post for binder-files which employ binder-bars, which consists of a fixed section provided with a slotted tongue, a movable section having in its body a slot adapted to inclose the tongue, a pin or stop passing through 90 the ends of the slotted movable section preventing the withdrawal of the movable from the fixed section, a sleeve or casing within which the fixed section is fixedly held, and a head screw-threaded into the end of the movable 95 section, substantially as described.

4. A post for binder-files which employ binder-bars which consists of a fixed section terminating in a screw-threaded stud and provided with a slotted tongue upwardly extending, a sleeve or casing within which the fixed section is fixedly held, a slotted movable section adapted to inclose the tongue and provided in its end with a screw-threaded recess, a pin passing through the end of the movable 100 section preventing its withdrawal from the fixed section, a stud screw-threaded into the recess in the end of the movable section, and a shell or casing of the same diameter as the sleeve or casing within which the stud is fixedly held and of a length to contact the end of the sleeve or casing when the extensible section has been forced downward to its limit, 105 substantially as described.

5. A post for binder-files which employ 110 binder-bars which consists of a fixed section, a sleeve or casing fixedly attached to the fixed section, an abutment extending across the sleeve or casing, a movable section provided in its end with a screw-threaded recess and 115

120

provided with a slot in its body through which the abutment passes, a stop at the end of the slot for preventing the withdrawal of the movable section, a stud screw-threaded into the recess in the movable section, and a shell or casing within which the stud is fixedly held of the same diameter as the sleeve or casing and of a length to contact the end of the sleeve

or casing when the movable section has been forced downward to its limit, substantially as described.
